Primary Examiner — Susan E Krakower(74) *Attorney, Agent, or Firm* — Andrew L. Salvatore, Esquire(57) **CLAIM**

The ornamental design for an exercise resistance device, as shown and described.

DESCRIPTION

FIG. 1 is a top plan view of an exercise resistance device showing my new design;

FIG. 2 is front elevation view of an exercise resistance device showing my new design;

FIG. 3 is a bottom elevation view of an exercise resistance device showing my new design;

FIG. 4 is a side elevation view of an exercise resistance device showing my new design;

FIG. 5 is a top plan view shown in condition of use; and,

FIG. 6 is a top plan view shown in an alternate condition of use.

The broken lines illustrate portions of the exercise resistance device which form no part of the claimed design.
